UNITED STATES PATENT OFFICE.

THOMAS B. JEFFERY, OF KENOSHA, WISCONSIN.

CURRENT-DISTRIBUTER AND CIRCUIT-BREAKER FOR GAS-ENGINE IGNITERS.

SPECIFICATION forming part of Letters Patent No. 740,020, dated September 29, 1903.

Application filed November 24, 1902. Serial No. 132,579. (No model.)

To all whom it may concern:

Be it known that I, THOMAS B. JEFFERY, a citizen of the United States, residing at Kenosha, in the county of Kenosha and State 5 of Wisconsin, have invented new and useful Improvements in Current-Distributors and Circuit-Breakers for Gas-Engine Igniters, of which the following is a specification, reference being had to the accompanying drawings, forming a part thereof.

The purpose of this invention is to provide an improved appliance for controlling the current in charging and discharging the secondary coil to produce the igniting spark in 15 a cylinder of a gas-engine, and specifically it is designed for the purpose of distributing the current to the several cylinders in the order of their operation in an engine having a plurality of cylinders and making it possible 20 to employ a single secondary coil for the purpose of furnishing the igniting-spark in the several cylinders of such an engine.

In the drawings, Figure 1 is a plan of my improved distributor, showing the brackets 25 by which it is designed to be mounted in any convenient position on the carriage or frame of the engine. Fig. 2 is a vertical section at the line 2 2 on Fig. 1. Fig. 3 is a vertical section at the line 3 3 on Fig. 1. Fig. 4 is a 30 plan of the contact-spring in the primary circuit. Fig. 5 is a side elevation of a motor-vehicle containing my improved devices, the side of the body of the vehicle being broken away to disclose the interior mechanism.

35 It will be understood that the ignition is effected in each cylinder by a spark produced as the discharge of a secondary coil, occurring when the primary or charging circuit is broken. I have not shown the cylinders nor the terminals of the igniting-circuit therein and have shown the primary and secondary coils and circuits only diagrammatically, because the specific location or form of the sparking devices and other physical 45 elements of the circuits or of the igniting devices are not material to my invention, which may be applied to any gas-engine in which ignition is effected by the spark in a secondary circuit.

50 A is a case, which is mounted by means of a bracket A' on the carriage, said case and bracket being of metal and the case being

thus adapted to be part of an electric circuit with the frame of the carriage.

B is a shaft journaled vertically in the 55 bracket A' at the center of the case and having another journal-bearing in the bracket C, which is also mounted on the carriage. At the lower end of the shaft B a pinion B' affords means by which the shaft may be rotated, and it is contemplated that in the case of a four-cycle two-cylinder engine it shall be driven by such geared connection with the main crank-shaft of the engine as to make one revolution for each two revolutions of 60 such main crank-shaft.

Within the case A, toward the upper part, there are mounted two metallic cheeks D D on insulating-blocks D' D', such cheeks being at diametrically opposite positions and 70 curved approximately in arcs of a circle about the axis of the shaft B and constituting terminal contact-pieces for the secondary circuit. The shaft is terminated within the case by an insulating block or cap B², upon which 75 there is mounted a spring-shoe or terminal contact-piece B²⁰, which extends over the end of the shaft past the center and is in contact at the center with the terminal contact-piece E, supported on the insulating-block E', which 80 is mounted on the inner wall of the case. From one end of the secondary coil N the wire-circuit n is connected to said contact-piece E, extending through the aperture a in the case to reach said terminal. From 85 the other end of the secondary coil the circuit-wire extends branched at n' to the sparking devices (indicated at w' w²) in two cylinders of the engine, (the device being here illustrated in a form suitable to be applied to an 90 engine having two cylinders only.) From said sparking devices, respectively, the wires n² n³ extend to the two terminal contact-pieces D D, respectively. The spring-shoe 95 B²⁰ is arranged to come into contact with the terminal contact-pieces D D as the shaft revolves, and when in contact with either one it completes the secondary circuit through the sparking device in the cylinder to which the wire runs from such cheek. Thus each 100

sparking device is thrown into the secondary circuit once in each revolution of the shaft B and remains in the circuit during a portion of that revolution dependent upon the extent

of the cheek or terminal contact-piece D. G is a terminal contact-piece supported on an insulating-block H, which is mounted on the inner wall of the case A toward the bottom 5 of the latter opposite an aperture a^2 in the case, through which a wire x of the primary circuit leading from the primary coil X enters and is connected to said terminal contact-piece. The primary circuit may include 10 the shaft B and its bearings and the frame on which said bearings are mounted. On the shaft B, below the terminal insulating-block B², there is a collar J, having two lugs or wings J' J', projecting at diametrically 15 opposite positions, each sloped upon the upper surface similarly with respect to the rotation of the shaft. On a plate L, which rests on the bottom of the case A and is secured to the case by the screw l, there is mounted 20 a terminal contact-piece consisting of the spring K, which being secured at one end has the other end free and overhanging the path of rotation of the forward points of the wings or lugs J' J' and in the path of rotation of the upper inclined faces of said lugs, so that as the shaft revolves said lugs successively enter under and crowd upward said free 25 end of the spring K, which is thereby brought into contact with the under side of the contact-piece H, which overhangs said free end of the spring. The contact thus established closing the primary circuit is broken when the spring drops off the abrupt heel j' of the lug J'. The several contact-pieces are so 30 disposed about the shaft B and with respect to the position of the spring-shoe B²⁰ and the lugs J' J' as to cause the order of action as the shaft revolves in the direction of the arrow on Fig. 1 to be as follows: Starting from 35 the position in which the parts are shown in Fig. 1, at which no contacts are established, the spring-shoe B²⁰ first comes into contact with the cheek D at one side, thus closing the secondary circuit through the sparking device of one cylinder. While this contact continues the wing J' on the cam J enters under 40 the end of the spring K and as the shaft revolves crowds said shaft up into contact with the contact-piece G, thereby closing the primary circuit and causing the secondary coil 45 to be charged, and a little later when the heel of the cam runs off the spring K, the primary circuit being thereby broken, the secondary coil is discharged by a spark at w' in one of the cylinders, and a little later the 50 secondary circuit is broken by the shoe B²⁰ running off the cheek D. All these contacts and circuit-breakings occur during one half revolution of the shaft, which corresponds to 55 the full cycle of action in one of the cylinders, and they are all duplicated in the same order during the other half of the revolution of the shaft B, corresponding to the full cycle of the other cylinder. Thus at each revolution 60 of the shaft B the secondary circuit is first established through a branch containing the sparking device of one cylinder. Then

the primary circuit being established the secondary coil is charged, and next the primary circuit being broken said coil is discharged 70 by a spark at said sparking device. Next the secondary circuit through that branch is broken, and the process consisting of the same steps is repeated through the other half of the revolution, the secondary circuit being 75 made through the other branch to cause explosion in the other cylinder. This structure, it will be observed, requires but one primary and one secondary coil in order to operate any desired number of cylinders, for it will 80 be seen that the number of cheeks D D and wings J' may be made to correspond to the number of cylinders, the same relation being preserved between each of them and the spring-shoe B²⁰, the spring K, and contact-piece 85 G, as above indicated.

The plate L, carrying the spring, is arranged to have a limited range of adjustment about the shaft by providing an elongated slot a' through the case for the screw l, which secures the plate, as stated above. This affords facility for varying with the limits of such adjustment the time of sparking. The contact-piece G, it will be noticed, is extended sufficiently to allow the maximum change of 95 position of the spring K which the length of the slot a' permits.

I claim—

1. A current distributor and breaker for explosive-engines, comprising a primary and secondary coil, and primary and secondary circuits including said coils respectively; a shaft revolved by the engine in uniform time relation thereto; a non-rotative element associated with the shaft; circuit closing and breaking devices in the secondary circuit having their coöperating terminal contact-pieces mounted respectively on the shaft and on the non-rotative element associated therewith; coöperating terminal contact-pieces for the primary circuit, both mounted on the non-rotative element and insulated from each other, the shaft being provided with means for establishing the primary circuit through said contact-pieces during a certain portion 115 of the shaft's revolution.

2. A current distributor and breaker for explosive-engines, comprising a primary and secondary coil, and primary and secondary circuits including said coils respectively; a shaft revolved by the engine and in uniform time relation thereto; a non-rotative element associated with the shaft, and circuit closers and breakers for the secondary circuit having their coöperating terminal contact-pieces 120 mounted respectively on the shaft and on the non-rotative element; coöperating terminal contact-pieces for the primary circuit both mounted on the non-rotative element and insulated from each other, the shaft being provided with means for mechanically forcing 125 said contact-pieces into contact as the shaft revolves.

3. A current distributor and breaker for

- an explosive-engine, comprising a primary and a secondary coil, and primary and secondary circuits including said coils respectively; a shaft revolved by the engine, and in uniform time relation thereto; a non-rotative case inclosing a portion of said shaft; insulated coöperating terminal contact-pieces in the secondary circuit mounted on said case, a corresponding insulated terminal contact-piece on the shaft, and an insulated conducting-bridge on the case making contact with the insulated terminal contact-piece on the shaft at the center of the latter; terminal contact-pieces for the primary circuit both mounted on the non-rotative case and insulated from each other; the shaft having a projection arranged to establish the primary circuit through said contact-pieces during a certain portion of the revolution of the shaft.
4. A current distributer and breaker for explosive-engines, comprising a primary and a secondary coil, and primary and secondary circuits including said coils respectively; a shaft revolved by the engine in uniform time relation thereto; a non-rotative case inclosing a portion of said shaft; insulated terminal contact-pieces for the secondary circuit mounted on said case, a corresponding insulated terminal contact-piece on the shaft and an insulated conducting-bridge on the case, making contact with said insulated terminal contact-piece on the shaft at the center of the latter; and terminal contact-pieces for the primary circuit mounted on the non-rotative case and insulated from each other, the shaft being provided with means for mechanically forcing said terminal contact-pieces into contact as the shaft revolves.
5. A current-distributer and circuit-breaker for an explosive-engine, having a plurality of explosion-chambers, comprising a primary and a secondary coil and primary and secondary circuits including said coils respectively; a shaft revolved by the engine and in uniform time relation thereto; circuit closers and breakers carried thereby for the primary and secondary circuits respectively; a non-rotative case which incloses the portion of said shaft which carries said closers and breakers; insulated terminal contact-pieces in the secondary circuit, mounted on said case, corresponding insulated terminal contact-pieces on the shaft, and an insulated conducting-bridge on the case making contact with said insulated terminal contact-piece on the shaft at the center of the latter; and terminal contact-pieces for the primary circuit, both mounted on the case and insulated from each other, and adapted to be forced into contact by the primary circuit-closer as the shaft rotates.
6. A current distributer and breaker for an explosive-engine having a plurality of explosive-chambers, comprising a primary and secondary coil and primary and secondary circuits including said coils respectively; the secondary circuit having branches extending to the sparking devices in the explosion-chambers respectively; a shaft revolved by the engine, and in uniform time relation thereto, circuit closers and breakers carried by said shaft for the primary and secondary circuits respectively; a non-rotating case which encompasses the portion of the shaft which carries the circuit closers and breakers; contact terminals for the respective branches of the secondary circuit, mounted and insulated on said case, and a single corresponding terminal contact-piece mounted and insulated on the shaft; the primary circuit having its contact-pieces both mounted on the case and insulated from each other; the shaft having the circuit breakers and closers for said primary circuit corresponding in number, and distribution about the shaft, to the number and distribution of the branches of the secondary circuit extending to the explosion-chambers respectively.
7. In combination with a case, A, and a shaft journaled therein rotated by the engine and in uniform time relation thereto, a primary circuit comprising said case and a contact-piece and a spring, both mounted on the case and one of them insulated therefrom and normally out of contact with the other; and a plurality of cams on the shaft in position to encounter said spring and force it against said contact-piece as the shaft revolves.
8. In a device for the purpose indicated, a case and a shaft journaled therein rotated by the engine in uniform time relation thereto; a contact-piece and a spring mounted on the case and normally out of contact with each other, one of them being insulated from the case; a primary circuit in which said case, contact-piece and spring are comprised; cams on the shaft arranged to force the spring against the contact-piece as the shaft revolves; said cams corresponding in number and distribution about the axis of the shaft to the number and distribution in the complete cycle of the engine's action of the explosions in the several explosion-chambers thereof; combined with a secondary circuit which comprises an insulated contact-piece carried by the shaft, and a plurality of coöperating insulated contact-pieces mounted on the case, corresponding in number and distribution about the shaft-carried piece to the number and distribution throughout the complete cycle of the engine's action of the explosions in the several chambers thereof, and in position respectively to be encountered by the shaft-carried piece during the closure of the primary circuit caused by such cam, and of such extent as to remain in contact after the breaking of the primary circuit.
9. In combination with the case, A, and shaft journaled therein, the primary circuit comprising said case and a contact-piece mounted thereon; one of said parts being insulated from and the other electrically connected with the case; a second contact-piece mounted on the case and movable into and

out of contact with the first-mentioned contact-piece; and a plurality of cams on the shaft, arranged to control the movement of said movable contact-piece into and out of contact with the other as the shaft revolves.

10. In combination with the case, A, and shaft journaled therein, rotated by the engine in uniform time relation thereto, a primary circuit comprising said case, and two contact-pieces mounted on the case and insulated from each other, one of them being movable into and out of contact with the other; and cams on the shaft arranged to control the movement of the movable piece into and out of contact with the other piece as the shaft revolves.

11. In a device for the purpose indicated, a case, and a shaft journaled therein, rotated by the engine in uniform time relation thereto, two contact-pieces mounted on the case and insulated from each other, one of them being movable into and out of contact with the other; a primary circuit in which said contact-pieces are comprised; cams on the shaft, arranged to control the movement of the movable pieces into and out of contact with the other as the shaft revolves; said cams corresponding in number and distribution about the axis of the shaft to the number and distribution in a complete cycle of the engine's action of the explosions in the several explosion-chambers thereof; combined with a secondary circuit which comprises an insulated contact-piece carried by the shaft and a plurality of coöperating insulated contact-pieces mounted on the case corresponding in number and distribution about the path of the shaft-carried piece to the number and distribution throughout a complete cycle of the engine's action of the explosions in the several chambers thereof, and in position respectively to be encountered by the shaft-carried piece during the closure of the primary circuit caused by such cam, and of such extent as to remain in contact after the breaking of the primary circuit.

12. In combination with the case, A, and a shaft journaled therein, rotated by the engine and in uniform time relation thereto, a primary circuit comprising two contact-pieces mounted on the case and insulated from each other, one of them being movable into and out of contact with the other; a plurality of cams on the shaft, arranged to control the movement of the movable piece into and out of such contact as the shaft revolves.

13. In a device for the purpose indicated, the primary circuit comprising a case, A, a shaft journaled in the case and revolved by the engine in uniform time relation thereto, and a contact-piece on said case; one of said parts being insulated and the other not insulated from the engine-frame; a spring mounted on the case, and cams on the shaft arranged to force the spring against said contact-piece as the shaft revolves, said cams

corresponding in number and distribution about the axis of the shaft to the number and distribution in the complete cycle of the engine's action of the explosions in the several explosion-chambers thereof; combined with a secondary circuit which comprises an insulated contact-piece carried by the shaft, and a plurality of coöperating insulated contact-pieces mounted on the case, corresponding in number and distribution about the path of the shaft-carried piece to the number and distribution throughout the complete cycle of the engine's action of the explosions in the several chambers thereof, and in position respectively to be encountered by the shaft-carried piece during the closure of the primary circuit caused by said cams, and of such extent as to remain in contact after the breaking of the primary circuit.

14. In a device for the purpose indicated, the primary circuit, comprising a case, A, and its metal supports on the engine-frame; an insulated contact-piece on said case; a spring mounted on the case; and cams on the shaft, arranged to force the spring against said contact-piece as the shaft revolves, said cams corresponding in number and distribution about the axis of the shaft to the number and intervals in the complete cycle of the engine's action of the explosions in the several explosion-chambers; combined with a secondary circuit comprising a contact-piece carried by the shaft, and a plurality of coöperating terminal contact-pieces mounted on the case, corresponding in number and distribution about the path of the shaft-carried piece to the number and distribution throughout the complete cycle of the engine's action of the explosions in the several chambers thereof, and in positions respectively to be encountered by the shaft-carried contact-piece during the closures of the primary circuit caused by said cams.

15. In combination with the case, A, and shaft journaled therein, the primary circuit, comprising said case, and a contact-piece mounted thereon; one of said parts being insulated from and the other electrically connected with the engine-frame; a spring mounted on the case and normally out of contact with said contact-piece; and a plurality of cams on the shaft in position to encounter said spring and force it against said contact-piece as the shaft revolves.

16. In combination with a gas-engine, a current-distributer, and a circuit-breaker for the igniters of the explosion-chambers, comprising a vertical shaft revolved in uniform time relation to the engine crank-shaft; an upwardly open case at the upper end of said shaft, rigidly mounted with respect to said frame, said case and shaft having all inclosed within the case coöperating circuit closing and opening contact-pieces for the primary and secondary circuits, arranged to be visible from above the case.

17. In combination with a motor-vehicle, a current-distributer and circuit-breaker for the igniters of the explosion-chambers of the motor, comprising a vertical shaft revolved in uniform time relation to the engine crank-shaft; an upwardly open case at the upper end of said shaft rigidly mounted on the vehicle-frame, said case and shaft having all inclosed within the case circuit-closing contacts for the primary and secondary cir-

cuits of the igniter, arranged to be visible from above the case.

In testimony whereof I have hereunto set my hand, in the presence of two witnesses, at Kenosha, Wisconsin, this 21st day of October, 1902.

THOS. B. JEFFERY.
